(57) **CLAIM**

The ornamental design for a walking frame, as shown and described.

DESCRIPTION

FIG. 1 is a front perspective view of a walking frame showing my new design;

FIG. 2 is a front view of the walking frame thereof;

FIG. 3 is a back view of the walking frame thereof;

FIG. 4 is a left side view of the walking frame thereof;

FIG. 5 is a right side view of the walking frame thereof;

FIG. 6 is a top view of the walking frame thereof; and,

FIG. 7 is a bottom view of the walking frame thereof.

The broken lines shown in the drawings are included for the purpose of illustrating environmental structure and form no part of the claimed design.
